UNITED STATES PATENT OFFICE.

JOHN HAYS HAMMOND, JR., OF GLOUCESTER, MASSACHUSETTS.

RADIODYNAMIC RECEIVING SYSTEM.

Application filed August 20, 1917, Serial No. 137,082. Renewed July 7, 1923.

To all whom it may concern:

Be it known that I, JOHN HAYS HAMMOND, Jr., a citizen of the United States, and a resident of Gloucester, in the county 5 of Essex and Commonwealth of Massachusetts, have invented an Improvement in Radiodynamic Receiving Systems, of which the following description, in connection with the accompanying drawings, is a specification, like characters on the drawings representing like parts.

This invention relates to means for and methods of simplifying the manipulation of radio-dynamic receiving systems that employ 15 beat reception, and is intended particularly to facilitate the operation of tuning in such systems or in any system employing audible beats.

In order that the principle of the invention may readily be understood I shall set 20 forth one form of means for practicing the invention and the best mode known to me for carrying the same into effect.

The drawing represents diagrammatically 25 a portion only of a radio-dynamic receiving system having one type or form of my invention applied thereto.

Referring more particularly to the drawing, I have indicated at 1, 2, terminals of 30 a radio-dynamic receiving system and upon which are impressed in some well-known manner, not herein necessary to more fully describe, the high frequency electrical oscillations with which it is desired to beat. Extending from the terminal 1 are three leads 35 or conductors 3, 4, 5 connected respectively to condensers 6, 7, 8. Said terminals 1, 2 extend to and are provided with the inductance coil 9, which is inductively coupled 40 with the coil or winding 10. Leading from the inductance coil 10 are conductors 11, 12, and from the former extend conductors 13, 14, 15 respectively extending to and connected with condensers 16, 17, 18. The conductor 12 extends to and is provided with inductance coil 19.

The condensers 6, 7, 8, the inductance coil 9, the condensers 16, 17, 18, and the inductance coils 10, 19, form the tuner or transformer which is to be properly resonated 50 with the high frequency impressed upon the terminals 1, 2.

I have indicated at 20 an inductance coil leading from which are conductors 21, 22, 55 and extending therefrom respectively are conductors 23, 24, 25, 26, 27, 28, with which

are operatively associated or connected, as shown, the condensers 29, 30, 31, 32. The circuit including the said inductance coil 20 and the condensers 29, 30, 31 is the main 60 oscillating circuit of an oscillating gaseous detector 31'. The said circuit through the inductive coupling between 19, 20, impresses upon the circuit 10, 19, 16, 17, 18 a high frequency differing from the received high 65 frequency by a certain or desired amount. In said circuit 10, 19, 16, 17, 18, therefore, there are thus superimposed the two high frequency oscillations, thus giving rise to the well-known phenomenon of beats, the 70 beat frequency being determined by the difference between the two high frequencies to which I have referred.

From the inductance coil 19 extends a lead 75 or conductor 33, which is connected to some suitable detector and preferably to the heated filament 34 of a gaseous detector 35 preferably of the audion type. The terminal 11 extends to a condenser 36 and from thence extends a conductor 37 leading to the 80 grid 38 of the said gaseous detector 35. In circuit with said heated filament 34, by means of conductors 39, 40, are batteries 41 42, and a variable resistance 43. Leading from the battery 42 is a conductor 44 extending to a condenser 45, and leading from the latter is a conductor 46, 47 extending to the plate 48 of the gaseous detector 35. The conductors 44, 47 extend to, and have connected therewith, the inductance coil 48. 85

By extending the terminals 11, 33, to the gaseous detector 35, or some other suitable type of detector, and if the circuit 45, 48 is adjusted so that its natural period is that of the beats hereinbefore referred to, the 90 said circuit 45, 48 will be fed by rectified groups having the frequency of the said beats, and hence the said circuit will build up strongly.

I have represented at 49 a coil inductively 95 coupled with the coil 48, and from which lead terminals 50, 51, connected with which is a condenser 52. The said circuit 49, 52 thus inductively coupled to the circuit 45, 48, may also be resonated to this beat frequency and the terminals 50, 51 extend from it to any desirable detector, as, for example, a pair of telephones, not herein shown. By providing a pair of telephones or other 100 means affording audible reception, I secure 110 advantages which are of peculiar importance in the use of my invention.

In carrying out my invention I provide a movable member or means, preferably in the form of a switch, and for the purpose I have herein represented a switch 53 of the 5 rotary fan-blade type, and pivotally mounted at 54, it being rotated in any suitable manner. As herein shown, the said switch is provided with three metallic sectors or blades 55, 56, 57, which are insulated from each other and are spaced equi- 10 angularly. Each of the said blades, as the switch is rotated, short-circuits the group of contact points 58, 59, 60, 61, 62, 63, 64, 65, 66 of the respective conductors 58^a, 59^a, 60^a, 61^a, 62^a, 63^a, 64^a, 65^a, 66^a leading respectively from the condensers 17, 7, 6, 8, 31, 29, 30, 15 16 and 18.

The results of such short-circuiting are threefold, namely; first, the tuning of the 20 circuit 6, 7, 8, 9; second, the tuning of the circuit 10, 16, 17, 18; and third, the changing of the frequency of the oscillation generator 31' attached to the circuit 20, 29, 30, 31. The condensers 6, 7, 8, 16, 17, 18, 29, 30, 31 are 25 preferably so adjusted at the time of assembling them that as the switch 53 is rotated a point at a time the circuits 6, 7, 8, 9, and 10, 16, 17, 18 remain properly in resonance, and at the same time the frequency of 30 the oscillation generator is maintained different from that of the said impressed frequency by a constant amount or, in other words, the beat frequency is to be maintained constant.

35 This enables the circuits 45, 48, and 49, 52 to remain fixed throughout, and it also results that the telephone or telephones preferably employed subsequent to the circuit 49, 52 may always be maintained at that frequency at which they are the most sensitive, and which in practice may be in the neighborhood of one thousand cycles per second.

In the drawing I have indicated only three 45 adjustments or positions of the rotary switch 53, but it is to be understood that this number may be increased without limit.

The condenser 32 is preferably a variable condenser for the reason that in practice it has been found that an oscillating gaseous 50 detector does not give rise to a frequency determined solely by the constants of its main oscillating circuit. The frequency depends on the filament heating current and the high voltage applied to a slight extent. The preferably small, variable condenser 32 is introduced mainly for the purpose of affording fine adjustment to compensate for the vagrancy of the oscillating gaseous detector.

The principle herein disclosed is particularly applicable in a system making use of a complex emitted wave form consisting of a high frequency and a secondary frequency above the limit of audibility by which signals are made through the variation of such 60 secondary frequency and are made audible 65

at the receiving station by beating to such secondary frequency. Since both the high and the secondary frequencies are above audibility in the preferred or typical receiving system to which I have referred, the tuning 70 up of a receiving system to a transmitting system is ordinarily quite tedious, involving as it does, feeling about or experimenting for two frequencies simultaneously. I preferably standardize both the transmitting 75 and the receiving sets during manufacture, the transmitting set being standardized to emit high frequency waves whose frequencies may be designated by the Figures 1, 2, 3, 4 etc., and whose secondary frequencies 80 may be designated by the letters A, B, C, D etc. The receiving station is calibrated to this same high and secondary frequencies, which are here designated in the same manner on the switch point. 85

It will be evident from the foregoing description that by the disclosed method I greatly simplify the tuning up of a receiving system, and particularly a system making use of the complex emitted wave form 90 consisting of a high frequency and a secondary frequency above the limit of audibility. 95

Having thus described one illustrative embodiment of my invention and the best mode known to me for practicing the same, I desire it to be understood that, although specific terms are employed, they are used in a generic and descriptive sense, and not for purposes of limitation, the scope of the invention being set forth in the following 100 claims. 105

Claims—

1. The combination with an oscillatory circuit, of means arranged to simultaneously 105 impress upon said circuit two series of periodic impulses having different frequencies respectively to produce periodic electrical beats in said circuit, means to change the tuning of said circuit, and means controlled 110 by said second-mentioned means for varying the frequency of one of said series of impulses and maintaining the frequency of said beats constant. 115

2. The combination with an oscillatory circuit normally tuned to respond to periodic electrical impulses of a predetermined frequency, of means associated with said circuit for impressing thereon periodic electrical impulses having a frequency different 120 from said first-mentioned frequency to produce electrical beats in said circuit, means for varying the tuning of said circuit, and means controlled by said second-mentioned means for varying the frequency of the oscillations produced by said first-mentioned means to maintain the frequency of said beats constant. 125

3. The combination with an oscillatory circuit including a primary tuning element, 130

of a second oscillatory circuit controlled by said first-mentioned circuit and including a primary tuning element, a secondary tuning element associated with each of said circuits, 5 means also associated with said circuits for impressing upon one of them a local frequency to produce beats in said circuits, a movable element, and means controlled by said element for causing said primary tuning 10 elements to act simultaneously either independently of said secondary tuning elements or in combination with said secondary tuning elements to control the tuning of said circuits and to maintain said circuits in resonance and to simultaneously change said 15 local frequency in such a manner as to maintain the beat frequency constant.

4. The combination with an oscillatory circuit including a primary tuning element, 20 of a second oscillatory circuit controlled by said first-mentioned circuit and including a primary tuning element, a secondary tuning element associated with each of said circuits, means also associated with said circuits for 25 impressing upon one of them a local frequency to produce beats in said circuits, a rotatable element, and means controlled by said element for causing said primary tuning elements to act simultaneously either in- 30 dependently of said secondary tuning elements or in combination with said secondary tuning elements to control the tuning of said circuits and to maintain said circuits in resonance and to simultaneously change 35 said local frequency in such a manner as to maintain the beat frequency constant.

5. In a receiving system for electrical oscillations, the combination with a receiving circuit tuned to a given frequency, of a sec- 40 ond circuit connected to and controlled by said first mentioned circuit and tuned to said frequency, a local source of energy ar- ranged to produce oscillations of a frequency different from said first mentioned frequency 45 and to act upon one of said circuits to pro- duce electrical beats therein, and a single movable element, and means controlled there- by for simultaneously changing the tuning of said circuits from the said given fre- 50 quency to another predetermined frequency

and at the same time changing the frequency of said oscillations produced by said local source to such an extent as to maintain the frequency of said beats constant.

6. In a receiving system, the combination 55 with an oscillatory circuit tuned to a given frequency, of a second oscillatory circuit in- ductively connected to said first mentioned circuit and tuned to the same frequency, a local source of energy arranged to produce 60 in one of said circuits oscillations having a frequency different from said first mentioned frequency and thereby to produce electrical beats, and a rotary element and means con- trolled thereby whereby upon the rotation of 65 said element the tuning of said circuits may be simultaneously changed from said given frequency selectively to any one of a plu- rality of other frequencies and at the same time said rotary element will operate to 70 change the frequency of the oscillations produced by said source and to such an extent as to maintain the frequency of said beats constant.

7. In a receiving system, the combination 75 with a receiving circuit tuned to a given fre- quency, of a second circuit inductively con- nected to said first mentioned circuit and tuned to the same frequency, a local source of energy arranged to act inductively upon 80 said second mentioned circuit to produce os- cillations therein having a frequency dif- ferent from said first mentioned frequency whereby electrical beats are produced in said second mentioned circuit, and a movable ele- 85 ment and means controlled thereby whereby the frequency to which said circuits are tuned and the frequency of the oscillations produced by said local source may be changed in such a manner that the frequency of one 90 of said circuits will always be the same as the frequency of the other of said circuits, and the frequency of said oscillations pro- 95 duced by said source will be so changed as to maintain the frequency of said beats con- stant.

In testimony whereof, I have signed my name to this specification.

JOHN HAYS HAMMOND, JR.
